object to always carrying the tools about in the usual way, it is desired to have a tool holder which will hold the tools in a compact manner, yet be held sufficiently apart from one another to prevent rattling when mounted on a moving vehicle.

UNITED STATES PATENT OFFICE

2,529,372

TOOLHOLDER

Robert Burns, Barksdale Field, La.

Application May 27, 1946, Serial No. 672,664

4 Claims. (Cl. 211—89)

1

My invention relates to tool holders generally, but more particularly to a tool holder adapted to be placed within the glove compartment of an automobile or the like.

In devices disclosed by the prior art various means of holding tools are shown, but it will be noted that they are usually placed in a box, rack, or the like, in the rear of the vehicle, or hung upon some support in the room, as the case may be. It is well known that the rear accessory compartment of the average person's automobile, and especially the tool kit, which is usually placed therein, is seldom kept in orderly fashion or in a manner where commonly used tools may be readily found and removed for use.

It is also known that the usual method of storing tools, whether in a kit or box, allows the tools to vibrate or rattle by coming in contact with one another, if kept in a moving vehicle, causing great annoyance to the occupants of the vehicle.

A further disadvantage found in the ordinary tool kit is that the small, commonly used tools are usually placed together with the larger ones that are seldom used. Thus, it becomes necessary, even when desiring to use such a tool as a screwdriver, to either handle, remove or replace many other large or heavy tools before finding or being able to remove the tool desired.

Since the usual work done to an automobile is not of a major nature, but minor repairs and the like, I have found my invention greatly advantageous by being capable of holding within easy reach, and in orderly fashion, only those tools that I might ordinarily use for making minor adjustments to an automobile or the like.

The general purpose of my invention is to provide a small tool holding device, capable of being mounted in the glove compartment of an automobile, a cabinet or the like, which will hold within easy, accessible reach of the user, such commonly used tools as pliers, screwdriver, air gauge, wrenches or any such small tools that are constantly required by the user; and where it is desired to have them readily accessible at any time.

It is another object of my invention to provide a tool holder which is substantially adjustable for holding various sizes of tools of the character described.

A still further object of my invention is to provide a device for holding tools with a firm, but releasable grip, in a compact manner, yet held sufficiently apart from one another to prevent rattling when mounted on a moving vehicle.

My invention comprises mainly, loops formed of rubber tubing lengths, the ends of which tubing

are cut slightly slanted to keep them from binding when forced over the studs, as will be described in detail hereinafter.

To draw the loops apart, a pair of pliers is used to grip the tubing and draw it deep into the base member.

It is an object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

It is another object of my invention to provide

a small tool holder which is adjustable and easily made.

a small tool holder which is adjustable and easily made.

It is another object of my invention to provide

a small tool holder which is adjustable and easily made.

admit the inserted tool, yet small enough to permit it to be held in place by the resiliency and flexibility of the rubber tubing, and be easily withdrawn therefrom.

Fig. 3 shows in plan view the arrangement of the spaced tubings forming the carriers for the inserted tools.

After passing through the choke ring 18 and forming the first mentioned loop 19, the tubing is then directed along the base 10 at right angles to the stud 13, but at a distance away from the base to form a flexible strap member 21 for holding a wrench W or the like; the resiliency of the rubber tubing being depended upon to hold this tool in a firm but releasable manner against the base member 10. The tubing length 17 is extended further through another choke ring 18 where it is extended parallel to the stud 14 and thereafter formed into another loop 19 with its open end fitting snugly over the lower stud 14, and into which second loop 19 another tool might be placed, such as the gauge G shown in Figure 1.

Referring again to Fig. 1, it will be seen that a similar construction is presented on the opposite end of the base member 10 where another length of rubber tubing 17 is connected to the projecting studs 15 and 16 in the aforementioned manner to form other loops 19 and another strap member 21 for holding the wrench W or some other tool.

As will be further noted from the drawings and description of my invention, it is possible to insert or withdraw any tool from my tool holder without interfering with the other tools that it contains.

It will be noted also that, by adjusting the slideable choke rings 18 mounted on the various studs, either up or down along the length of the stud, an appreciable variation may be obtained in the size and area of the various loops 19 and the straps 21 formed by the manner in which I have bent the length of rubber tubing 17, to accommodate various sizes of tools.

I purposely space the loops 19 close enough together in pairs to utilize them as yieldable finger-like members adapted to hold an additional tool in the pinching manner in which they are shown holding the pliers P in Fig. 1 of the drawing. The pair of loops 19 perform this pinching holding operation without interfering in any way with the above described manners of holding a tool—the first manner being the yielding of the side of the loop to accommodate a tool—the second function being the stretching of the tube to accommodate a tool.

While I have described my invention in detail in its preferred form, it is not intended that it shall be limited either to the materials stated or be confined to use in an automobile, but may be used to advantage anywhere a compact, anti-rattling, resilient tool holder is desired.

Having thus described my invention I claim:

1. A tool holder of the class described comprising a base plate adapted to be attached to a

wall surface, a pair of spaced lengths of elastic tubing each of which is attached to said base plate at opposite ends, portions of said lengths of tubing being formed into loops and adjustable choke rings embracing doubled portions of said lengths of tubing, said choke rings being made small enough to yieldingly clamp portions of said lengths of tubing on other portions of said tubing, whereby the lengths of said loops may be adjusted to cooperate in holding a tool.

2. A tool holder as claimed in claim 1 wherein said loops are positioned to lie in spaced substantially parallel planes whereby one of said loops is adapted to receive a tool extended through a loop at the opposite end of the plate.

3. A tool holder of the class described comprising a base plate adapted to be attached to a wall surface, a length of elastic tubing attached to said plate at both of its ends, said ends being attached to said base plate in spaced relationship, in a manner to extend said length of elastic tubing outwardly from said base plate, said elastic tubing having portions of its length formed into a pair of spaced collapsed loops connected by an integral portion of said elastic tubing constituting a flexible strap, said loops being formed in said length of elastic tubing by means of a pair of choke rings forced over doubled portions of said length of elastic tubing, said length of elastic tubing being slidably mounted in said choke rings whereby the length of said loops and said flexible strap may be adjusted by movements of said choke rings or movements of said length of elastic tubing through said choke rings.

4. The tool holder as claimed in claim 3 provided with a second length of elastic tubing mounted on said base plate substantially parallel to said first mentioned length of elastic tubing and provided with a pair of choke rings each of which is extended over doubled portions of said second mentioned length of elastic tubing in a manner to divide the same into a second pair of loops and a flexible strap positioned substantially parallel to said first mentioned loops and said first mentioned strap, whereby said second mentioned loops and said second mentioned strap may cooperate with said first mentioned loops and said first mentioned strap in holding tools.

ROBERT BURNS.
